UNITED STATES PATENT OFFICE

132,254

DESIGN FOR A PLAQUE OR SIMILAR ARTICLE

Walter Roy Harvey, Quarryville, and Joseph Tyson Henry, Jr., and Harry Neilson Flavell, Jr., York, Pa.

Application June 5, 1940, Serial No. 92,836

Term of patent 3½ years

To all whom it may concern:

Be it known that we, Walter Roy Harvey, a citizen of the United States of America, residing at Quarryville, in the county of Lancaster and State of Pennsylvania, Joseph Tyson Henry, Jr., a citizen of the United States of America, residing at York, in the county of York and State of Pennsylvania, and Harry Neilson Flavell, Jr., a citizen of the United States of America, residing at York, in the county of York and State of Pennsylvania, have invented a new, original, and ornamental Design for a Plaque or Similar

Article, of which the following is a specification, reference being had to the accompanying drawing, forming part thereof, wherein Fig. 1 is a plan view of the plaque or similar article, showing our new design; and Fig. 2 is an edge view of the plaque shown in Fig. 1.

We claim:

The ornamental design for a plaque or similar article, as shown.

WALTER ROY HARVEY.
JOSEPH TYSON HENRY, JR.
HARRY NEILSON FLAVELL, JR.
